UNITED STATES PATENT OFFICE.

JOHN W. SUTTON, OF NEW YORK, N. Y.

GAIT-STRAIGHTENING ATTACHMENT.

SPECIFICATION forming part of Letters Patent No. 657,798, dated September 11, 1900.

Application filed June 2, 1900. Serial No. 18,828. (No model.)

To all whom it may concern:

Be it known that I, JOHN W. SUTTON, a citizen of the United States, residing in the city of New York, borough of Brooklyn, and 5 State of New York, have invented certain new and useful Improvements in Gait-Straightening Attachments, of which the following is a specification.

This invention relates to an improved attachment for vehicle-shafts by which the gait of horses may be straightened—*i. e.*, the habit of horses of pressing their hind parts toward the shaft may be corrected—and a straight and even motion of the horse secured. A 10 large number of “light-harness horses,” both trotters and pacers, have a more or less side-wise movement—that is to say, they carry their hind parts over against the shaft of the vehicle, putting the right hind foot under the 15 left fore foot so the toe of the shoe on the fore foot during the forward movement strikes the front of the hind hoof. This is known as “scalping.” The sidewise movement renders it impossible for the horse to travel as 20 easily or as rapidly as if going straight. The sidewise movement is toward the left in some horses and in others toward the right. For 25 the purpose of correcting this habit my invention consists of a gait-straightening attachment which comprises a pad, springs supporting the same, means for adjusting the position of the pad on said springs, means for attaching said springs to the vehicle-shaft, and means for limiting the movement of the 30 pad-supporting springs; and the invention 35 consists, further, in certain other combinations of operative parts, which will be more fully set forth and claimed hereinafter.

In the accompanying drawings, Figure 1 is 40 a perspective view of my improved gait-straightening attachment. Fig. 2 is a front elevation of the attachment. Fig. 3 is a side elevation of the same; and Fig. 4 is a plan view, partly in horizontal section, on line 44, 45 Fig. 2.

Similar letters of reference indicate corresponding parts.

Referring to the drawings, A represents a cushioned pad covered, preferably, with 50 leather. The pad may be of any suitable shape and is preferably rotatably mounted, with its axis approximately parallel with the

shafts. The shaft upon which the pad is supported is carried by clips *aa*, that are attached to and adjustable upon stout wire springs *C*, 55 the lower ends of which are coiled and provided above the coils with hook-shaped ends supported in sleeves at the ends of a clip-plate *D'*, which is secured to the vehicle shaft by means of an upper clip *D* and fastening-screws *d d* and a screw-nut and bolt *d'*. The clip-plate *D* is hinged to eyes of the fastening-screws. By means of the fastening-screws and bolt the distance between the two clip-plates may be readily adjusted, so as to permit clamping the attachment rigidly upon a shaft *S* of any diameter or at any point in the length of the shaft. The lower clip-plate *D'* is provided with an upright post *D²*, carrying at its upper end a cross-piece that is connected by adjustable leather straps *E* with the clips *aa*, supporting the pad *A*. 60 70 75

For correcting in a horse the habit referred to the attachment is slipped upon the shaft toward which the movement takes place to a point opposite the ribs of the horse or thereabout. The horse is then harnessed to the vehicle and the attachment clamped to the shaft in the desired location by turning up the nut on the bolt *d'*. The clips *aa* are then 80 adjusted upon the springs *C C*, if necessary, so as to bring the pad to proper height. Lastly, the straps *E E* are adjusted so as to permit the pad *A* to project the proper distance from the shaft toward the horse. Upon 85 driving the horse he attempts to assume his uneven gait; but in doing so his ribs press against the pad and he is unable to assume a position out of line with the shafts, but must travel squarely, without unevenness of gait. 90 By continuous use of the gait-straightener the habit is gradually broken up and the device may be dispensed with, to be used again should the habit recur.

Side straps and side poles extending from 95 the end of the shaft back to the cross-bar of the shafts have been used heretofore for correcting the habit referred to. They have the great disadvantage, however, of presenting the resistance to the sidewise movement upon the 100 moving or pulling muscles of the horse. These muscles contact with these strap and pole devices, and the action of the horse is seriously interfered with. My device, however, contacts

with the horse upon or near the ribs and not upon the working muscles and does not interfere with or impair his action, but corrects the sidewise movement. The attachment has the 5 great advantage that it is perfectly adjustable—*i. e.*, adjustable in every direction—so that the pad can be brought to bear with exactness where required. It is furthermore spring-actuated, so as to present a yielding 10 resistance, whereby injury to the animal cannot possibly occur.

Having thus described my invention, I claim as new and desire to secure by Letters Patent—

15 1. A gait-straightening attachment for vehicle-shafts, consisting of a pad, springs supporting the same, means for adjusting the position of the pad on said springs, means for attaching said springs to the vehicle-shaft, 20 and means for limiting the movement of said pad-supporting springs, substantially as set forth.

2. A gait-straightening attachment for ve-

hicle-shafts, consisting of a pad, springs supporting the same, means for attaching said 25 springs to the vehicle-shaft, an upright post on said attaching means, and adjustable straps connecting said post with said springs for limiting the movement of the latter, substantially as set forth.

30

3. A gait-straightening attachment, consisting of a pad, supporting-springs, clips securing said pad to said springs and adjustable thereon, a clip device for attaching said springs to the shaft of a vehicle, an upright 35 post on said clip device, and adjustable straps connecting said clips with the post, substantially as set forth.

In testimony that I claim the foregoing as my invention I have signed my name in presence of two subscribing witnesses.

JOHN W. SUTTON.
